(57) **CLAIM**

The ornamental design for a display screen or portion thereof with animated graphical user interface as shown and described.

DESCRIPTION

FIG. 1 is a front view of a display screen or portion thereof with animated graphical user interface showing a first image in a sequence according to our new design;

FIG. 2 is a front view thereof showing a second image in the sequence;

FIG. 3 is a front view thereof showing a third image in the sequence;

FIG. 4 is a front view thereof showing a fourth image in the sequence; and,

FIG. 5 is a front view thereof showing a fifth image in the sequence.

The outer peripheral broken lines illustrate a display screen or portion thereof and forms no part of the claimed design. The remaining broken lines illustrate portions of the animated graphical user interface that form no part of the claimed design.

The appearance of the animated image sequentially transitions between the images shown in FIGS. 1-5.

The process or period in which one image transitions to another form no part of the claimed design.
